CLAIM

The ornamental design for a modular spare tire mount for accessories, as shown and described.

DESCRIPTION

FIG. 1 is a top perspective view of a modular spare tire mount for accessories, showing our new design;

FIG. 2 is a bottom perspective view thereof;

FIG. 3 is a front elevational view of FIG. 2;

FIG. 4 is a rear elevational view of FIG. 2;

FIG. 5 is a top plan view of FIG. 2;

FIG. 6 is a bottom plan view of FIG. 2;

FIG. 7 is a left-side elevational view of FIG. 2, the right-side elevational view being a mirror image thereof;

FIG. 8 is a cross-sectional view thereof, taken along line 8--8- of FIG. 2; and,

FIG. 9 is a cross-sectional view thereof, taken along line 9--9 of FIG. 2.

The broken lines showing of the top platform, side mounting plates, and a wheel, in FIG. 1, illustrates the environment of the claimed design and forms no part thereof.
